UNITED STATES PATENT OFFICE.

WALTER L. BOCKOVER, OF TIPTON, INDIANA.

WRENCH.

1,370,510.

Specification of Letters Patent.

Patented Mar. 8, 1921.

Application filed October 29, 1920. Serial No. 420,417.

To all whom it may concern:

Be it known that I, WALTER L. BOCKOVER, a citizen of the United States, residing at Tipton, in the county of Tipton and State of Indiana, have invented a new and useful Wrench, of which the following is a specification.

This invention has reference to tools, and more particularly to wrenches, it being the primary object of the invention to provide a wrench which will automatically adjust itself to the article to which the same is applied.

A further object of the invention is to provide a device of this character which will increase its gripping action on the article, during the rotation of the wrench to position the pipe or article under operation.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:—

Figure 1 illustrates a plan view of a wrench constructed in accordance with the present invention.

Fig. 2 is an elevational view of the wrench.

Fig. 3 is a sectional view taken on line 3—3 of Fig. 1.

Fig. 4 is a sectional view taken on line 4—4 of Fig. 1.

Referring to the drawing in detail, the wrench includes a head 5 and a handle section 6, the head comprising a pair of circular members 7 disposed in spaced relation with each other as by means of the semi-circular member 8, there being provided securing bolts 9 passing through suitable openings in the circular members 7 and spacing member 8.

Formed in one of the walls of the members 7 and 8 are the teeth 10, which teeth co-operate with the teeth 11 formed on one end of the handle 6 for gripping a pipe or the like to accomplish the rotation thereof, the portion of the handle 6 on which the teeth 11 are formed, being inclined to insure a firm gripping of the article under operation.

The handle portion 6 is pivotally supported between the circular members 7 at a point intermediate the ends of the semi-circular member 8, as by means of the pivot pin 12.

In the use of the device, the head is positioned over a pipe or the like, and the handle is rotated to cause the teeth 11 thereof to force the pipe into engagement with the teeth 10, whereupon the pipe is gripped between the wrench and teeth. It is obvious that when the handle portion is moved in the opposite direction, the teeth release their hold on the pipe, and the wrench is permitted to move on the pipe, whereupon the same may be gripped by pressure brought to bear on the handle 6.

Having thus described the invention, what is claimed as new is:—

A wrench including a head and handle section, said head comprising rigid circular plates, means disposed between the plates for supporting the plates in spaced relation with each other, said handle portion being pivotally supported between the plates and having one end thereof lying within the confines of the circular plates and having teeth formed on one edge thereof, and said plates having teeth adapted to coöperate with the teeth of the handle portion.

In testimony that I claim the foregoing as my own, I have hereto affixed my signature in the presence of two witnesses.

WALTER L. BOCKOVER.
